US00D790477S

(12) **United States Design Patent** (10) **Patent No.:** **US D790,477 S**
Ruddick (45) **Date of Patent:** **** Jun. 27, 2017**

(54) **CABLE CONDUIT**

(71) Applicant: **D-Line (Europe) Limited**, Tyne and Wear (GB)

(72) Inventor: **Paul David Ruddick**, Tyne and Wear (GB)

(73) Assignee: **D-Line (Europe) Limited**, Tyne and Wear (GB)

(**) Term: **15 Years**

(21) Appl. No.: **29/558,930**

(22) Filed: **Mar. 23, 2016**

Related U.S. Application Data

(62) Division of application No. 29/466,905, filed on Sep. 12, 2013.

(57) **CLAIM**

The ornamental design for a cable conduit, as shown and described.

DESCRIPTION

FIG. 1 is a bottom front perspective view of a cable conduit showing the claimed design;
FIG. 2 is a top rear perspective view thereof;
FIG. 3 is a side view thereof;
FIG. 4 is another side view thereof;
FIG. 5 is another side view thereof;
FIG. 6 is another side view thereof; and,
FIG. 7 is a top view thereof.
The shade lines in the drawings show contour and not surface ornamentation.

(Continued)

The broken lines in the figures show portions of the cable conduit that form no part of the claimed design.

1 Claim, 2 Drawing Sheets
